UNITED STATES PATENT OFFICE.

LESLIE G. BOWEN, OF KANSAS CITY, MISSOURI.

TROLLEY-POLE CLAMP.

1,049,657.

Specification of Letters Patent.

Patented Jan. 7, 1913.

Application filed June 2, 1911. Serial No. 630,800.

To all whom it may concern:

Be it known that I, LESLIE G. BOWEN, a citizen of the United States, residing at Kansas City, in the county of Jackson and State of Missouri, have invented new and useful Improvements in Trolley-Pole Clamps, of which the following is a specification.

The invention relates to clamps, and more particularly to the class of trolley pole clamping devices for use on trolley cars.

The primary object of the invention is the provision of a clamp in which a trolley pole, when in lowered position, will be held fast, and when it is desired to have the trolley wheel contact with the overhead wire, it is only necessary to pull downwardly upon the pole while in lowered position, whereupon the same will be freed from the clamp.

Another object of the invention is the provision of a clamp of this character in which the trolley pole, when locked therein, will be prevented from rising, thereby sustaining its wheel from the overhead electric wire.

25 A further object of the invention is the provision of a clamp of this character which is simple in construction, thoroughly reliable and efficient in its purpose, and inexpensive in manufacture.

30 With these and other objects in view, the invention consists in the construction, combination and arrangement of parts, as will be hereinafter more fully described, illustrated in the accompanying drawings, and pointed out in the claims hereunto appended.

In the drawings: Figure 1 is a fragmentary perspective view of a car roof, showing a trolley pole mounted thereon and lowered into engagement with the clamp for holding the said pole in such position, the clamp being constructed in accordance with the invention. Fig. 2 is a vertical longitudinal sectional view through the clamp showing the pole locked therein. Fig. 3 is a similar view, with the clamp in releasing position. Fig. 4 is a perspective view of one of the locking members removed from the clamp. Fig. 5 is an enlarged fragmentary vertical sectional view through the clamp, showing the pole engaged with the catch device and in the act of passing the same.

Similar reference characters indicate corresponding parts throughout the several views of the drawings.

Referring to the drawings by numerals, 5 designates a portion of the roof of a car, 55 on which is mounted in the ordinary well-known manner a trolley pole 6, the latter being of the usual type and is adapted to be raised and lowered, as usual, and when in 60 lowered position will be locked by means of a clamp, presently described.

The clamp comprises a base plate 7, from which rises a housing, the same being formed of spaced vertically disposed channeled uprights or posts 8, the channels 8' therein opening through the inner edges of the said posts or uprights. These uprights or posts 8, at their upper ends, are rounded at their inner edges, so as to form a wide 70 entrance to the space between the said posts or uprights, whereby the trolley pole, when lowered, will freely pass into the said space between the uprights or posts 8 for holding the trolley pole in lowered position by 75 means of catch mechanism, presently described.

Mounted within the channels 8' in the posts or uprights 8, near the upper ends thereof, are opposed locking elements, comprising substantially L-shaped catch members 9, the same being mounted upon pivots 10 passed transversely through the uprights or posts and said members, each member being formed with an outwardly tapered tip 85 11 at one end, while its opposite end is formed with a short substantially right angular extension 12 provided with flat faces 10', 11' and 12', the faces 11' being normally engaged and overlapped by the free 90 ends of the resilient limbs 13 of a U-shaped spring member 14, the latter being movably fitted in the channels in the uprights or posts 8, and has a limited vertical sliding movement therein, so that on the lowering 95 of the said spring member 14, the free ends of its limbs 13 will slide from the flat faces 11' below the flat faces 10' of the catch members 9, thereby permitting them to be swung outwardly for the freeing of the 100 trolley pole 6, the spring member 14 being moved to lowered position in a manner presently described.

Interposed between the uprights or posts 8 and engaging the flat faces 12' of the 105 catch members 9 are leaf springs 15, the same being engaged at their lower ends with cross pins 15' mounted in the posts or

uprights 8, while their upper free ends rest against the end walls of the said housing, as will be seen in Figs. 2, 3 and 5 of the drawings, the spring 14 being designed to act upon the catch members 9 so as to hold the tips 11 in alignment with each other to permit the said catch members to rock upon the pivots 10 when the pole 6 is being lowered and contacts with the tips 11, so that the 5 said pole 6 will enter the space between the uprights or posts 8, and also when the said pole 6 is being elevated the tips 11 of the catch members 9 will swing upwardly and outwardly away from each other to permit 10 the said pole 6 to pass between the catch members and out of the entrance in the housing of the clamp for the contact of its 15 wheel with the overhead trolley wire.

The free ends of the limbs 13 of the 20 spring 14, when engaged with and overlapping the flat faces 11' of the catch members 9, are prevented from being moved toward each other by means of the cross pins 17 which are fixed transversely of the 25 channels 8' in the vertical uprights or posts 8, so that it will be impossible for the catch members 9, at their tips 11, to swing upwardly and outwardly when the spring member 14 is elevated, and the free ends 30 of the limbs 13 are engaged with the said catch members, in a manner hereinbefore described.

Interposed between the closed end of the 35 U-shaped spring member 14 and the base plate 7' is an upwardly bowed leaf spring 16 which is adapted to move the said spring 14 upwardly in the channels in the posts or 40 uprights 8, when the right angular portions 12 of the said catch members 9 have been swung out of the path of movement of the free ends of the limbs 13 of the said spring members 14, and on the rising of the spring member 14 its free end will abut the flat 45 faces 10', so that when the trolley pole 6 rises in the space between the uprights or 50 posts 8 and contacts with the tips 11 of the catch members, the latter will freely swing upwardly and outwardly, thereby allowing the trolley pole 6 to pass the tips and become freed from the clamp.

In the operation of the clamp, the parts thereof are normally in the position shown in Fig. 2 of the drawings, that is to say, prior to the lowering of the trolley pole 6 55 in the clamp, and on the lowering of the said pole, the same contacts with the tips 11 of the catch members 9, causing them to slightly rotate on their pivots 10 in a downward direction against the resistance of the 60 spring 16, thus permitting the pole 6 to enter the space between the uprights 8 and become locked in the housing of the clamp. It will be apparent that the catch members 9 will be prevented from swinging upwardly and outwardly for the freeing of 65

the pole 6 by reason of the overlapping of the free ends of the limbs 13 of the spring member 14.

Now, should it be desired to release the trolley pole 6 so as to permit the same to rise, whereby its wheel will contact with the overhead electric wire, it is only necessary to pull downwardly upon the pole 6, bringing it in contact with the closed end of the spring member 14, causing it to lower 70 with the pole, thereby sliding the free ends of the limbs 13 of the said spring member from the faces 11' of the right angular portions of the catch members 9, causing the said free ends to ride below the flat 75 faces 10' of the said extensions of the catch members. Thus on the raising of the pole 6 against the tips 11 of the same, they will swing upwardly and outwardly permitting the pole 6 to pass the catch members and 80 become freed from the clamp. On again lowering the pole 6 into contact with the tips 11 of the members 9, they will be rocked on their pivots 10 in a downward direction, so that the free ends of the limbs 85 13 of the spring member 14 will clear the right angular extensions of the catch members, and upon the rising of the spring member 14, the said free ends will engage and 90 overlap the flat faces 11' and assume the 95 position shown in Fig. 2 of the drawings, thereby locking the trolley pole 6 in lowered position in the clamp.

It is clearly evident that when the pole 6 is lowered and engaged in the clamp, the 100 same will be securely held in such position, and when pulling downwardly on the pole, causing the lowering of the spring member 14, the catch members will be free for raising the pole, whereby it may swing to 105 raised position to bring its trolley wheel in contact with the overhead electric current wire.

What is claimed is:

1. A trolley pole clamp comprising a 110 shell adapted to be mounted upon the roof of a car and having a central elongated opening extending through the top thereof for receiving a trolley pole, latch means within the shell and intersecting the opening for retaining said pole when engaged therein, and means within the shell and in the path of movement of the pole for engagement therewith when lowered to free the latch means to permit the release of 115 the pole from the opening in the shell.

2. A pole clamp comprising a shell 120 adapted to be secured to a car and having a central elongated opening extending through its top for receiving a trolley pole 125 when lowered, latch members pivotally mounted in the shell and intersecting the opening and means mounted within the shell and engaging the said latch members for sustaining the said pole within the open- 130

ing within the shell when inserted therein, and on contact of the pole therewith the said means will free the latch members to allow the pole to disengage from the opening in the shell.

5. The combination with a trolley pole of a device comprising a base having spaced vertically disposed channeled uprights between which the pole is adapted to swing, locking jaws pivoted in the channeled uprights and engageable with the pole and a 10 slideable spring member mounted in the up-

rights for normally holding the jaws in position for sustaining the pole between said uprights and adapted for lowering movement by the pole to free the jaws for releasing the said pole from between the uprights. 15

In testimony whereof I affix my signature in presence of two witnesses.

LESLIE G. BOWEN.
